IRONING DEVICE

Solomon H. Seidman, New York, N. Y., and
Arthur F. Routh, New Haven, Conn.

Application March 6, 1930, Serial No. 433,632

8 Claims. (Cl. 68—9)

This invention relates to devices for ironing and pressing fabrics, and more particularly to the type in which the material to be ironed or pressed is propelled on a roller.

One of the objects of the invention is to provide a stationary heated iron normally separated from and adapted to contact with a padded axially rotatable roller over which the material to be ironed is propelled. Another object is to control the rotation of the roller and contacting with the iron by means of a pedal, in order to leave the hands free for guiding the material, also to prevent possible burning of the material. A further object is to provide the device with a table and standard, which are collapsible, so that the device becomes portable. An additional feature is an automatic cut off provision for the heat supply to the iron and the rotation of the roller a predetermined interval after release of the foot control. Among the advantages are also simplicity of construction and operation.

These and other objects and advantages will be apparent from the drawings and description forming part of this specification; and the new and novel embodiments in the construction and arrangement of parts will be set forth therein and claimed. In the drawings,—

Fig. 1 is a plan view of the device set up for operation.

Fig. 2 is a front elevation of same.

Fig. 3 is an end elevation of same.

Fig. 4 is a section view on line 4—4 in Fig. 2, but showing the standard and table leaves collapsed.

Fig. 5 shows the electric circuit diagram.

In the construction shown to illustrate the invention, a roller 10 is pivoted in bearings 11 and 12 on supports 13 and 14 respectively. As in the usual ironing board, a padding and canvas covering 15 embraces the roller 10. To enable the mounting of certain garments over one end of the roller, an end roller 16 is provided with a hemispherical or otherwise curved contour 17. This end roller 16 is mounted on the same shaft with roller 10, but cantilevers out on the other side of the support 14. Roller 16 is covered by padding and canvas 18 similar to 15. If only roller 16 is to be used without exerting pressure on roller 10, a thicker layer of padding may temporarily be placed around roller 16.

A flat iron 19 is maintained over roller 10 and 16 by means of the supporting members 20 and 21 held in place by pins 22, as is evident in Fig. 2. The iron 19 here shown is preferably heated by the passage of electric current through the heat-

ing element 23 embodied therein. It is however also readily adaptable for being heated by gas.

The supports 13 and 14 are attached to a bed 24, which may comprise two angle irons 25 and 26, slightly deflected downwardly at their extremities. Pivottally attached at each end of each angle, is a standard 27, and each pair of standards is held from excessive lateral separation by the cross members 28, 29, which are pivotally connected to the standards 27 at 30 and 31 and to each other by pin 32. The pin 32 is adapted for upward movement above the horizontal only, whereby the free extremities of the standards 27 are brought toward each other. The standards may then be swung about their respective pivots and brought under the bed 24. On each side of roller 10, and pivotally mounted on supporting members 13 and 14 are the table leaves 33 and 34, which when opened up for use are each supported at their free extremities by the strut members 35, 36, and are held in a plane a short distance below the uppermost surface of roller 10. The strut members 35 and 36 are pivotally connected to the bed 24, the table leaves 33 and 34 and to each other, with a stop catch 37 near the latter connection. The leaves may thus be dropped when not in use, as shown in Fig. 4.

Pivottally connected to the bed 24 by pin 38 is the motor bed 39, which as illustrated here comprises also two angles 40 and 41, which are resiliently supported on bed 24 by the springs 42 and 43. A pin 45 through the angles 41 and 40, transmits to them the stress in the heating iron support 20, and has pivotally attached to it the bar 46. Another bar 47 is suspended from pin 48, on which is also mounted the support 21. A spring 49 attached to the bed 24 receives the stress from the support 21. A treadle 50 is supported from bars 46 and 47, and is adapted to slide upward along said bars as they are swung about their pivots up against the underside of the bed 24. Fig. 4 shows the standards 27, the treadle 50 and bars 46 and 47 on the underside of bed 24 and the table leaves 33 and 34 dropped to form the side walls of the collapsed device, which is compactly held together by tie-rods 51. Thus the device becomes portable and readily put away when not in use; yet it is adapted to be quickly set up.

An electric motor 52, mounted on a motor bed 39, has a speed reduction mechanism 53 and a pulley 54. On a pulley 55 concentric with roller 10 and in line vertically with pulley 54, is belt 56, adapted to contact with pulley 54 when the

motor bed 39 is depressed, and is thereby caused to revolve with pulley 54. When the motor bed is not depressed, pulley 54 contacts instead with a facing on pulley 57, which is keyed to a screw 58, and causes screw 58 to revolve with it. Hinged beneath the screw 58 is a rod 59 which has a pair of electric contactors 60 and 61 along most of its length and insulated from each other, and an insulator 62 for the balance of its length. An 10 electric contacting slider 63 is adapted to make connection between 60 and 61 to close an electric circuit as long as it slides along the contactors 60 and 61. But upon sliding past them on to the insulating portion 62, the connection between 15 these contactors is broken. The slider 63 is adapted to fit into the grooves of the screw 58, and as the screw revolves, the slider 63 is caused to move to the left as viewed in Fig. 2 or Fig. 5.

The electrical connections are shown in Fig. 20 5. A double prong plug 64 is adapted for connection to the source of electric power and is preferably connected by means of a flexible cord to two separate double pole switches 65 and 66. The current through the heating resistor 23 is applied by the switch 65, and the current through 25 the motor is independently applied by means of switch 66. The motor circuit includes in series, the top of switch 66, the wire connected to the portion of slider 63 contacting with strip 60, strip 60, contactor 69, rheostat 67, motor 52 and bottom of switch 66, also slider 63 acting only to contact strip 60, for this circuit. The heater circuit includes in series the top of switch 66, the wire connected to the portion of the slider 30 35 63 contacting with strip 60, slider 63, strip 61, wire to resistor 23 and bottom of switch 66.

The ordinary flat iron usually has a pointed portion, which is frequently an aid in ironing. To produce the equivalent effect, a pointed member 40 45 70 is provided. This may be a bent wire suitably shaped and adapted for insertion into any of the pairs of openings 71 in the iron frame 19. This is of distinct aid in flattening the seams of members sewed together. This provision of adjustability of mounting the guide member 70 at any point along the width of the ironer (normal to the direction of movement of the articles) permits the use of substantially the full ironer regardless of the position of the seam along the 50 55 width of the article ironed, also requiring less movement of the article in aligning of seam and guide member, by the mere movement of the guide member 70 to the nearest receptacle 71.

The operation of the device will be found simple. Assume the device is collapsed as shown in Fig. 4. To be set up for use, the tie-rods 51 are disengaged, the standards 27 are dropped and spread apart until the bed 24 rests solidly upon them, the treadle 50 is dropped down as the bars 60 65 46 are swung downward, the table leaves 33 and 34 are raised, and plug 64 is connected to the source of power supply. Switch 65 is then closed to energize the heating element 23 until the iron reaches the proper operating temperature. Then switch 65 is disconnected and switch 66 is closed, the garment is placed on leaf 33 and over rollers 10, 16 and treadle 50 is depressed with the foot. As the treadle is moved down the hot flat iron 19 is drawn down against the action of the springs 42, 43 and 49 until it contacts with the garment on roller 10, 16. At the same time that the motor bed 39 moves down, with the depression of treadle 50, member 68 moves with it and causes slider 63 to slide down toward the right end of the rod 59 which end had been lowered in elevation, and

thereby closes the motor and heating element circuits. Also as member 68 moves down, contactor 69 moves along resistor 67, reduces the resistance and thus causes the motor 52 to gradually speed up. Pulley 54 has also moved down and been brought to bear against belt 56, so that as the motor revolves, the belt 56 and consequently the pulley 55 and rollers 10, 16 revolve with it. The garment is thus carried forward by its frictional action against the roller, and the smooth hot surface of iron 19 produces the desired results, and the ironed garment emerges on table leaf 34. By removing the foot pressure from the treadle 50, the depressed springs 42, 43 and 49 rebound, thereby separating the iron from the garment; the roller immediately stops revolving because pulley 54 is drawn from belt 56; but instead the pulley contacts with the friction pulley 57 which thereby starts revolving. Member 68 also moves up and causes the motor to revolve more slowly by introducing resistance 67, also causing slider 63 to engage with the teeth of screw 58 which revolves with the pulley 57, whereby slider 63 is moved toward the left as viewed in Fig. 2. If the ironing is not resumed by depressing the treadle 50 within a reasonably short time, the slider 63 will have been moved until it no longer connects 60 and 61 but is on the insulated portion 62. The circuit is thus broken and the motor 52 stops revolving and the heating element 23 cools off. This provision of the time limit cut off is for the purpose of preventing the frequent starting and stopping of the motor; yet to prevent wasting of unnecessary current if the use of the ironer is not resumed within a reasonable time.

When the ironing is completed, the plug is removed from the power socket, the treadle and standards are collapsed in the manner indicated in dot and dash lines in Figs. 2 and 3 and the 40 compact unit resulting as shown in Fig. 4, is put away.

It will thus be seen that the embodiment of the various features of this invention have been fully described, that they attain the various objects of the invention and are well suited to meet the requirements of practical use. Of course the device need not be made collapsible and many changes can be made in the above construction and many apparently widely different embodiments of this invention could be made without departing from the scope thereof. It is therefore intended that all matter contained in the description and drawings shall be interpreted as illustrative and not in a limiting sense.

Accordingly what is claimed and desired to secure by Letters Patent is:

1. In an ironing device, in combination, a roller for propelling material, an ironing member in spaced relation to said roller, a motor, engagement means for operatively connecting said motor and roller, means for applying said ironing member to said roller and for actuating said motor and engagement means, and time controlled means for disconnecting the source of power supply to said motor a predetermined time interval after disengagement of said roller from the motor.

2. An ironing device comprising a supporting frame, an ironing member, a rotatable garment 70 propelling roller in spaced relation with said ironing member, a motor, engagement means for operatively connecting said roller to said motor, a foot control for applying said ironing member to said roller and for actuating said motor and 75

said engagement means and means for separating said ironing and roller members and for disengaging said roller from said motor when the foot is removed from said control and time controlled means for disconnecting the source of power supply to said motor a predetermined time interval after said disengagement.

3. In an ironing device, in combination, a supporting frame, an ironing member, heating means therefor, a rotatable garment propelling roller in spaced relation with said ironing member, a motor, engagement means for operatively connecting said roller to said motor, foot control for applying said ironing member to said roller and for actuating said motor and said engagement means, and time controlled means for disconnecting the source of power supply to said motor and said heating means a predetermined time interval after disengagement of said roller from the motor.

4. In an ironing machine having a roller and an ironing member extending parallel to the longitudinal axis of said roller, the combination of a guiding member, and a plurality of receptacles disposed throughout the length of said ironing member, each of said receptacles adapted to support said guiding member so that same may be set in operative relation to articles fed between said roller and ironing member.

5. In an ironing device the combination of an

ironing member, means for heating same, a garment propelling roller and driving means therefor, means for disengaging said roller from said driving means and time controlled means actuated by said disengaging means for disconnecting the power supply for said heating means a predetermined time interval after disengagement of said roller from said driving means.

6. In an ironing device of the class described, an iron, an article supporting member in operative relation to said iron, a pointed guide element on said iron and means whereby the position of said element along the width of said iron may be adjusted.

7. In a device of the class described, the combination of an iron, a heating device adapted to be energized to heat said iron, an article supporting member, means for applying pressure between said iron and said member, release mechanism therefor and time controlled means actuated by said release mechanism for deenergizing said heating device a predetermined time interval after the pressure applied between said iron and supporting member had been removed.

8. The combination with an ironing device of a guide element and means on said ironing device whereby the position of said guide element can be adjusted along the width of same.

SOLOMON H. SEIDMAN.
ARTHUR F. ROUTH.
